US00D998606S

(12) **United States Design Patent** (10) **Patent No.:** **US D998,606 S**
(45) **Date of Patent:** **** Sep. 12, 2023**

(54) **ELECTRONIC DEVICE**

(71) Applicant: **Apple Inc.**, Cupertino, CA (US)

(72) Inventors: **Jody Akana**, San Francisco, CA (US); **Bartley K. Andre**, Palo Alto, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Steven P. Jobs**, Palo Alto, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/678,139**

(22) Filed: **Jan. 25, 2019**

Related U.S. Application Data

(60) Continuation of application No. 29/572,745, filed on Jul. 29, 2016, which is a continuation of application No. 29/498,328, filed on Aug. 1, 2014, now Pat. No. Des. 763,253, which is a continuation of application No. 29/432,436, filed on Sep. 14, 2012, now Pat. No. Des. 710,843, which is a continuation of application No. 29/379,707, filed on Nov. 23, 2010, now Pat. No. Des. 672,343, which is a continuation of application No. 29/360,036, filed on Apr. 19, 2010, now Pat. No. Des. 627,778, and a division of application No.

29/363,172, filed on Jun. 5, 2010, now Pat. No. Des. 633,493, which is a continuation of application No. 29/360,110, filed on Apr. 20, 2010, now Pat. No. Des. 633,908.
